(57) **CLAIM**

The ornamental design in a pop screen filter assembly, as shown and described.

DESCRIPTION

FIG. 1 is a rear view of a pop screen filter assembly embodying my new design;

FIG. 2 is a front view of a fragment of FIG. 1 shown separately for purposes of illustration;

FIG. 3 is a left side view of FIG. 1;

FIG. 4 is a right side view of FIG. 1;

FIG. 5 is a top view of FIG. 4;

FIG. 6 is a bottom view FIG. 3;

FIG. 7 is a front, right side isometric view of the pop screen filter assembly embodying my new design; and,

FIG. 8 is a rear, left side isometric view of FIG. 7.
